[57] CLAIM

The ornamental design for a head bandage protector, as shown and described.

DESCRIPTION

FIG. 1 is a perspective view of a head bandage protector showing our new design, a head being shown in broken lines for illustrative purposes only and forming no part of the claimed design;

FIG. 2 is a front elevational view thereof;

FIG. 3 is a side elevational view thereof; and

FIG. 4 is a rear elevational view thereof.

The figures show the material of the head bandage protector as being an open-mesh, elastic textile material.
